UNITED STATES PATENT OFFICE.

FELIX ARRACHART, OF CHARENTON-LE-PONT, FRANCE.

STENCIL-PLATE.

1,111,429.

Specification of Letters Patent. Patented Sept. 22, 1914.

Application filed November 7, 1912. Serial No. 730,040.

To all whom it may concern:

Be it known that I, FELIX ARRACHART, a citizen of the French Republic, residing at No. 3. Avenue de Gravelle, Charenton-le-Pont, Seine, France, have invented a new and useful Improvement in Stencil-Plates, of which the following is a specification.

The stencil plates generally used together with a brush for printing type letters on cases, casks and the like are most inconvenient in that they are separated and are to be selected one after one when being used and are often mislaid, thereby causing important loss of time.

The present invention relates to a numbering stencil plate with cut out letters and signs which is made of metal or any other suitable material in the form of disks with varying cuts and having on its edges cut out figures from 0 to 9 as well as various abbreviations such as: kilo, gross weight, dead weight, net weight, and the like, or a certain number of the letters of the alphabet and so forth. The said disk carries at its center a stud and allows of printing readily any determined figures or signs, by rotating it by the hand for bringing and holding the cut out portions to be used in position, while the blackening by means of a pad is effected by the other hand. The disk may also be made in two pieces hinged together, being thus foldable and made more compact when not in use.

The invention will now be more fully described hereinafter with reference to the accompanying drawings in which:

Figure 1 is a top plan view of the cut out disk. Fig. 2 is a view partly in plan showing how the said plate can be used for a more spaced numbering. Fig. 3 is a similar view showing how the same is to be used for a more compact numbering. Fig. 4 is a top plan view of a modified form of the disk of Fig. 1.

Referring now to Figs. 1 to 3, the device is constituted by a metal disk (a) made of brass or any other metal material having stamped ribs (b) and other ribs (c) diverging from the center; but for reasons of manufacture and rigidity the ribs (b) can be limited to the length L under the figures and the ribs (c) can be completely done away with. Supposing in this example the disk carries adjacent its edges the figures 0 to 9, there will be ten divisions (d) ended by a straight portion (e) parallel to the axis

of the figure in each division and bent up at its edge, ending at a line (f) parallel to the neighboring rib, thus forming a notch (g). This arrangement allows of a perfect guiding of the device for bringing the same into position for the printing of the figures and for bringing the latter into alinement.

In Figs. 2 and 3 is shown the position to be given to the device, for instance, for printing the numbers 20 or 30 on a case or a cask provided with a registering line R. The printing is effected from right to left, the rib line (b) being used for the alinement of the figures horizontally, while the edge (e) is used for equally spacing each figure and for insuring the true vertical positioning of the same. The edge (f) of each notch is used as a base for the horizontal alinement in the case where the parcels, casks and the like should not have any registering line.

The normal spacing of the figures is effected as follows: The "unit" figure of a number having been traced, the edge (e) of the division corresponding to the "ten" figure is made to register with the edge of the "unit" figure, see Fig. 2: unit = 0; ten = 2. For a closer numbering (number 30 Fig. 3) after having traced the unit 0, the edge (e) of the division carrying the figure 3, is placed so as to more or less overlap the previously traced figure 0.

The operation is the same for the following figures, should the number to be traced comprise, three, four or more of them. The device may also have other signs or indications such as: kgs: dollars, gross weight, net weight and the like, cut in it between the inner circle G and the figures on the edges. Within the circle G is suitably fitted a stud (h) which allows of passing rapidly from a figure to another by holding said stud in one hand, the said stud being of such length, with reference to the hand of the operator, that the latter should be able to hold it in his hand and to press with the fore-finger and the middle finger on the disk for holding the same during the stenciling.

According to the arrangement shown in Fig. 4, the metal disk is made in two parts (i) (j) hinged or otherwise connected together as at (k) so as to form a complete circle when the device is unfolded and form a half-circle when folded, after having unscrewed the central stud. Obviously the

hinges (*k*), two or more in number, can be placed on any diametral line such as (*l*) or (*m*) or (*n*). Such diametral lines will be preferably indicated by grooves instead of 5 by ribs.

The indications: kgs, dollars, gross weight, etc., indicated in the first arrangement (Figs. 1 to 3) can be substituted for by small figures (0) arranged parallel to the 10 edge figures and cut out in the same way, by providing between them a cut out part (p) limited by the incurved edges (q).

Having now particularly described and ascertained the nature of my said invention 15 and in what manner the same is to be performed I declare that what I claim is:

1. A stencil plate of the character described comprising a disk provided with the characters 0 to 9 cut out of said disk adjacent the edge thereof and appropriate abbreviations between said edge and the center of said disk, a central stud, radial ribs on said disk for guiding said disk on

the surface to be stenciled upon, and for alining and spacing the characters upon said 25 surface, substantially as described.

2. A stencil plate of the character described, comprising a disk provided with the characters 0 to 9 and appropriate abbreviations grouped around the center of said 30 disk and cut out of the material of the same, a central stud providing a handle, ribs on said disk dividing the same into ten fields each field provided with a straight portion 35 forming a notch on the margin thereof for guiding said disk upon the surface to be stenciled upon and for spacing said characters upon said surface, substantially as described.

In testimony whereof I affix my signature 40 in presence of two witnesses.

FELIX ARRACHART.
